(57) **CLAIM**

I claim the ornamental design for a lighting device, as shown and described.

DESCRIPTION

FIG. 1 is a perspective view of a lighting device in a collapsed configuration showing my new design, as viewed from the top and one side.

FIG. 2 is a first side elevation view of the lighting device of FIG. 1 in the collapsed configuration.

FIG. 3 is a back elevation view of the lighting device of FIG. 1 in the collapsed configuration.

FIG. 4 is a second side elevation view of the lighting device of FIG. 1 in the collapsed configuration.

FIG. 5 is a front elevation view of the lighting device of FIG. 1 in the collapsed configuration.

FIG. 6 is a top plan view of the lighting device of FIG. 1 in the collapsed configuration.

FIG. 7 is a bottom plan view of the lighting device of FIG. 1 in the collapsed configuration.

FIG. 8 is a bottom plan view of the lighting device of FIG. 1 in the collapsed configuration and with extended base support portions; and,

FIG. 9 is a first side elevation view of the lighting device of FIG. 1 in an expanded position configuration and with an extended hook portion.

The details shown in broken lines illustrate portions of the lighting device that form no part of the claimed design.
